UNITED STATES PATENT OFFICE.

FRANK DIEHL, OF WABASH, INDIANA.

GLUE-MACHINE.

1,317,620.

Specification of Letters Patent. Patented Sept. 30, 1919.

Application filed February 27, 1917. Serial No. 151,259.

To all whom it may concern:

Be it known that I, FRANK DIEHL, a citizen of the United States, residing at Wabash, in the county of Wabash and State of Indiana, have invented a new and useful 5 Glue-Machine, of which the following is a specification.

The device forming the subject matter of this application is adapted to be employed 10 for heating and spreading glue, and one object of the invention is to provide novel means whereby a water seal for the lids of the glue pots is afforded, the water of condensation forming the water seal, and excess 15 water being returned to the glue pots.

Another object of the invention is to provide novel means whereby the glue is automatically fed from the glue pot to the glue spreader.

20 A further object of the invention is to improve the spreader.

Another object of the invention is to provide novel means whereby cold water may be supplied to the jackets of the glue pots, 25 when the glue pots are filled, and to provide novel means whereby this cold water can be drawn away, at the will of an operator.

It is within the province of the disclosure 30 to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the 35 invention herein disclosed can be made within the scope of what is claimed, without departing from the spirit of the invention.

In the accompanying drawings:—

Figure 1 shows in side elevation, a glue 45 machine constructed in accordance with the present invention, parts being broken away;

Fig. 2 is a vertical transverse section taken through the glue spreader, parts appearing in elevation;

Fig. 3 is an elevation wherein the structure is viewed at right angles to the showing of Fig. 1;

Fig. 4 is a vertical section taken through one of the casings and the glue pot which is 55 assembled therewith; and

Fig. 5 is a top plan showing a glue ma-

chine constructed in accordance with the present invention.

In carrying out the present invention there are provided casings 1 supported on 60 a pedestal 2. Each casing 1 adjacent its upper end is supplied with an inwardly projecting circumscribing lip 3 as shown best in Fig. 4.

Disposed within each casing 1 is a glue pot 4 having an outwardly projecting flange 5 supported on the lip 3 of the casing 1, the flange 5 having a shoulder 6 which, coacting with the inner edge of the lip 3 holds the glue pot 4 concentric with the casing 1 thereby to define, between 65

the glue pot and the casing, a jacket 48. In the upper edge of each glue pot 4 is formed a continuous circumscribing groove 7, the outer wall 8 of which is higher than the inner wall 9 thereof. The glue pots 4 are 70

provided with lids 10, each having a flange 11 extended downwardly into the groove 7. Lugs 12 are carried by the flange 5, and levers 14 are fulcrumed at 15 on the lugs, 75

the levers being pivoted at 16, intermediate 80 their ends, to ears 17 upstanding from the lids 10. The upper ends of springs 18 are connected with the outer ends of the levers 14, the lower ends of the springs being

united with offset brackets 19 attached to 85 the outer faces of the casings 1.

The invention comprises a spreader denoted generally by the numeral 20 and including an outer casing 22 supported on a 90 pedestal 21. Disposed within the outer cas-

ing 22, as shown best in Fig. 2, is an inner tank 23, equipped with a flange 24 supported on a flange 25 constituting a part of the outer casing 22, there being a jacket 26 95 between the inner tank 23 and the outer casing 22. In its side wall, the inner tank 23 is provided with an opening 27, about

which extends a hood 28 which may be formed integrally with or connected to the said side wall of the inner tank. The side 100 wall of the outer casing 22 of the spreader is provided with an opening 29 coaxial with the opening 27, but of a larger size than the opening 27.

Bearings 30 are mounted on the flange 24 105 of the inner tank 23, and in the bearings 30 are journaled shafts 31 carrying an applying roller 32 and a spreading and removing roller 32^a, extended downwardly into the inner tank 23 of the spreader. The shafts 31 110 carry intermeshing gear wheels 33, one of the gear wheels 33 meshing into a pinion 34

fixed to a drive shaft 35 journaled in a hanger 36 carried by the outer casing 22. Any suitable means may be provided for rotating the shaft 35, a pulley 37 and a belt 38 being shown in the present instance.

5 Mounted on the flange 24 of the inner tank 23 and disposed on opposite sides of the bearings 30 are brackets 39 to which up-standing arms 40 are pivoted as shown at 10 41. Screws 42 are carried by the brackets 39 and pass loosely through the arms 40. Springs 43 surround the screws 42, the inner ends of the springs 43 abutting against the arms 40, and the outer ends of the 15 springs abutting against hand wheels 44 which are threaded onto the screws 42. Shafts 69 are journaled in the arms 40, one of the shafts 69 carrying a doctor roller 45 driven by contact with the roller 32, and 20 the other of the shafts 69 carrying a wiping roller 45^a, driven by contact with the roller 32^a.

The numeral 46 denotes cold water pipes which communicate, as shown at 47, with the 25 jackets 48 between the glue pots 4 and the casings 1. Interposed in the pipes 46 are hand valves 49. Each pipe 46 has an upwardly prolonged branch 50 extended as shown at 51 into the jacket 48 and terminating in an exposed cock 52 located exteriorly of the casing 1. Leading from the parts 47 of the cold water intake pipes are drainage branches 53 in which are interposed hand valves 54. The drainage branches 53 communicate with drain pipes 55 which are upwardly and laterally extended as shown at 56, the parts 56 of the pipe 55 communicating with the jackets 48 between the glue pots 4 and the casings 1.

40 The numeral 57 marks a steam supply pipe which is prolonged horizontally as shown at 58 in front of the casings 1, the part 58 of the steam pipe having depending branches 59 which communicate with the jackets 48. Interposed in the branches 59 of the steam pipe are valves 60, and condensers 61 are also interposed in the branches 59. The steam pipe 57 has a branch 62 carrying a hand valve 63. The branch 50 62 opens through the outer tank 23 of the spreader and communicates with the jacket 26. A pipe 200 leads from the jacket 26 to one of the drain pipes 55.

Glue conveying pipes 64 are provided, the 55 same passing through the jackets 48 and communicating with the glue pots 4 as shown in Fig. 4. These glue pipes 64 are equipped with hand valves 65. The lower ends of the pipes 64 merge into a pipe 640 60 which enters the opening 27 in the inner tank 20 of the spreader, as shown in Fig. 2, the discharge end of the glue pipe 640 opening within the contour of the hood 28. The pipe 640 is surrounded, adjacent the 65 spreader 20, by a tubular jacket 66, the in-

ner end of which is mounted in the opening 29 of the outer casing 22 of the spreader. The outer end of the jacket 66 is connected with the pipes 640 adjacent the spreader 20 by means of a gland 67, the construction being such that the steam in the jacket 26 of the spreader may circulate in the jacket 66, and thus warm the glue before it enters the tank 23. The pipe 200 has a branch 201 leading to the jacket 66. 70

As is known in the art, the pots 4 must be cold when the glue is first dissolved. Assuming that the jackets 48 are empty of hot water, the valves 49 are opened, and the valves 54 are closed. Cold water then passes 80 by way of the pipes 46 and their branches 47 into the jackets 48 and accumulates therein until the jackets are substantially full, the excess cold water passing away through the pipes 56 into the drain pipes 55. The glue 85 is then mixed properly in the cold glue pots 4, and if the valves 49 are closed, the valves 54 being opened, the cold water in the jackets 48 will flow by way of the pipes 47 and 53 into the drain pipes 55. The valves 54 90 then are closed, and the apparatus is in such a condition that the glue can be heated up.

In order to heat the glue, the valves 60 are opened, and then steam traverses the pipe 57, the pipe 58 and its branches 59. 95 The steam, passing through the condensers 61, is turned into hot water which enters the jackets 48, the temperature of the water in the jackets 48 being determined by thermometers 68 carried on the exterior of the 100 casings 1. The overflow hot water in the jackets 48 passes by way of the pipes 56 into the drain pipes 55. The temperature of the water in the jackets 48 may be regulated by opening the valves 49, so as to admit a 105 supply of cold water from the pipes 46 into the jackets by way of the pipes 47.

The valves 65 are set to permit the desired flow of glue from the glue pots 4 through the pipes 64 and 640 into the inner tanks 23 of the glue spreaders 20. The glue pots 4 are hermetically sealed by the lids 10, and consequently, the glue will flow through the lower ends of the pipes 64 and 640 into the inner tank 23 of the spreader, only when the 115 glue in the inner tank 23 has been depleted enough so that air can enter the pipe 640 through the hood 28. This operation takes place automatically, to maintain, practically, a constant level of glue in the inner tank 120 23 of the spreader, and after the valve 65 have been set, they need be manipulated only for the purpose of regulating the amount of glue delivered.

The steam within the glue pots 4 accumulates on the lids 10 and runs downwardly and outwardly along the under surfaces of the lids, across the upper edge of the relatively low inner wall 9, into the grooves 7. When this water of condensation has ac- 130

5 cumulated sufficiently in the grooves 7, the water flows over the upper edge of the wall 9, and passes back into the glue pot 4. The flanges 11 on the lids 10 dip into the water 10 seal in the grooves 7, and thus the glue pots 5 seal are sealed hermetically. The springs 18, react on the levers 14, to hold the lids 10 down on the glue pots 4, it being possible 15 to detach the upper ends of the springs from the levers 14, or to detach the lower ends of the springs from the brackets 19 when it is desired to swing the lids 10 to open 20 positions, as takes place when the supply of glue in the pots 4 is to be renewed.

15 The branch 50 and its extension 51, together with the cock 52, constitute a means whereby a supply of hot water may be secured at any time. These parts have nothing to do with the operation of the machine, 20 so far as the melting or manipulation of the glue is concerned.

When the drive shaft 35 is rotated by means of the pulley 37 and the belt 38 or their mechanical equivalents, the pinion 34 25 on the drive shaft 35, meshing into one of the gear wheels 33, drives said gear wheel, and the said gear wheel drives the other gear wheel, the shafts 31 being rotated, and the applying roller 32 and the spreading 30 and removing roller 32^a being rotated in the direction of the arrows in Fig. 1. A board or like object, which is to be glued, is pushed across the tops of the rollers 32 and 32^a, in the direction of the arrow A of Fig. 1. 35 The roller 32 applies the glue to the board and the roller 32^a which rotates in an opposite direction to the roller 32, spreads the glue evenly over the board, and takes off the excess glue. By rotating the hand 40 wheels 44, the pressure of the roller 45 on the roller 32, and the pressure of the roller 45^a on the roller 32^a may be adjusted, the roller 45^a bearing on the roller 32^a with a stronger pressure than that exerted by the 45 roller 45 on the roller 32. The roller 45^a, therefore, wipes off the excess glue on the roller 32^a, the roller 32^a being, essentially, a glue spreading roller, whereas the roller 32 is a glue applying roller.

50 Steam from the pipe 62 is delivered into the jacket 26 of the spreader for heating purposes. The steam leaves the jacket 26 by the branch 201, the pipe 200 and one

5 pipe 55. This secures a heating of the glue as it is being delivered through the pipe 640 55 to the spreader. Because the pipe 200 opens at one end into the jacket 26 of the spreader in spaced relation to the branch 201 which connects to the part 66, there is a through 60 circulation of steam in the jacket 26 of the spreader, and all of the steam does not make a short-cut to the pipe 200 by the branch 201.

Having thus described the invention, what is claimed is:—

1. In a device of the class described, a glue pot; a spreader including an outer casing and an inner tank defining a space between the casing and the tank, the casing having a side wall, and the tank having 70 a side wall and a bottom; means for heating the contents of said space; a glue pipe leading from the pot to the tank and extended across said space and through both side walls; a tubular jacket surrounding a portion of the glue pipe exterior to the casing and having one end mounted in the side wall of the tank and in communication with said space; means for closing the outer end of the jacket about the pipe; and an arched 80 hood carried by the side wall and the bottom of the tank, the glue pipe discharging within the hood.

2. In a device of the class described, a glue pot having a jacket; a spreader having 85 a jacket; a glue pipe leading from the pot to the spreader; a jacket about the glue pipe and communicating with the jacket of the spreader; means for supplying steam to the jacket of the spreader; means for supplying steam to the jacket of the glue pot; means for supplying cold water to the jacket of the glue pot; a drain pipe leading from the jacket of the glue pot; and a steam outlet pipe leading from the jacket of the 95 spreader to the drain pipe and having a branch communicating with the jacket of the glue pipe.

In testimony that I claim the foregoing as my own, I have hereto affixed my signature in the presence of two witnesses.

FRANK DIEHL.
